(57) **CLAIM**

The ornamental design for the lighting fixture, as shown and described.

DESCRIPTION

FIG. 1 is a perspective view of a lighting fixture in accordance with the new design;
FIG. 2 is a front elevational view thereof;

FIG. 3 is a right side elevational view thereof, a left side elevational view being a mirror image thereof;
FIG. 4 is a bottom view thereof;

FIG. 5 is a perspective view of an alternative embodiment of the lighting fixture in accordance with the new design which is similar to FIG. 1 with the addition of crystals;
FIG. 6 is a front elevational view thereof;

FIG. 7 is a right side elevational view thereof, a left side elevational view being a mirror image thereof; and,

FIG. 8 is a bottom view thereof.
The broken lines in the drawings are for illustrative purposes only and form no part of the claimed design.
